[57] CLAIM

The ornamental design for a bird feeder, as shown and described.

DESCRIPTION

FIG. 1 is a front elevational view of a bird feeder showing my new design, the rear being the same as the front shown;

FIG. 2 is a side elevational view thereof, the opposite side being the same as the side shown;

FIG. 3 is a top plan view thereof;

FIG. 4 is a bottom plan view thereof;

FIG. 5 is a front elevational view of a modified form of the bird feeder shown in FIG. 1, the rear being the same as the front shown;

FIG. 6 is a side elevational view of FIG. 5, the opposite side being the same as the side shown;

FIG. 7 is a front elevational view of a second modified form of the bird feeder shown in FIG. 1, the rear being the same as the front shown; and

FIG. 8 is a side elevational view of FIG. 7, the opposite side being the same as the side shown.

The top and bottom of the modified forms are the same as the top and bottom shown in FIGS. 3 and 4 respectively.

FIG. 1

FIG. 2

FIG. 4

FIG. 3

FIG. 5

FIG. 6

FIG. 7

FIG. 8
